Inventor: James H. Winterowd,
By Thomas G. Orwig, Attorney,

UNITED STATES PATENT OFFICE.

JAMES H. WINTEROWD, OF LEGRAND, IOWA.

EXTENSIBLE HAME FOR HORSE-COLLARS.

SPECIFICATION forming part of Letters Patent No. 774,141, dated November 1, 1904.

Application filed January 22, 1903. Serial No. 140,193. (No model.)

To all whom it may concern:

Be it known that I, JAMES H. WINTEROWD, a citizen of the United States, residing at Le-
grand, in the county of Marshall and State of
Iowa, have invented a new and useful Exten-
sible Hame for Horse-Collars, of which the fol-
lowing is a specification.

My object is to provide improved means for
lengthening and shortening hames to fit on
horses and collars of different sizes and to pre-
vent the top ends of the hames from projecting
above the collars and horses, so that the break-
ing of hames incident to extending above a
horse's neck and the rubbing of horses against
fixed objects will be avoided.

My invention consists in means for adjust-
ably connecting two overlying end portions of
a hame and covering the connected ends, as
hereinafter set forth, pointed out in my claims,
and illustrated in the accompanying drawings,
in which—

Figure 1 is a perspective view of one of a
pair of hames that may be advantageously used
on different-sized horses. Fig. 2 is a trans-
verse sectional view on the line $\alpha\alpha$ of Fig. 1
and shows the overlying parts of the upper
portion of the hame that are slidably connect-
ed. Fig. 3 on the line $\gamma\gamma$ of Fig. 1 shows the
overlying parts latched together as required
to retain them stationary when properly ad-
justed for use on collars of different sizes.
Fig. 4 is a transverse sectional view on the line
 $\beta\beta$ of Fig. 1 and shows the overlying lower por-
tions of the hame adjustably connected and a
metal cover fitted and fixed thereto. Fig. 5
is a plan sectional view that shows to what ex-
tent the upper and lower portions of the hame
may overlap each other.

The numeral 10 designates the upper por-
tion, and 12 the lower portion, of a wooden
hame adjustably connected. Parts of their
inner side portions are cut away so they can
overlap each other and slide longitudinally
relative to each other, as required to lengthen
and shorten a hame. A longitudinal slot 13
in the upper part 10 allows a bolt 14, having
a head 15, to be extended through the slot and
fixed in the part 12 by riveting or in any suit-
able way, so that the bolt can traverse the
slot when the part 10 is moved up or down on
the part 12. The part 12 is also provided
with a slot 13 and a bolt 15, passed through

the slot and fixed in the part 10 to slidably con-
nect the part 10 with the part 12.

A metal cover 16 is fixed to the upper part 55
10 and a corresponding cover 17 to the part
12 in such a manner that they conceal the ends
of the overlying parts.

The upper end portion of the part 12 is pro-
vided with a series of notches 18 and the lower 60
portion of the part 10 with a single corre-
sponding notch 19 and a spring-latch 20, fixed
to the edge of the part 10, so that a stop 21
on the end of the latch will enter the notches
in the part 12 when they coincide with the 65
notch in the part 10, and thus lock the two
parts together, as required for practical use.

Having thus described the purpose, con-
struction, and operation of my invention, its
practical utility will be readily understood by 70
persons familiar with harness-hames, and

What I claim as new, and desire to secure
by Letters Patent, is—

1. In a hame for horse-collars, a top end por-
tion and a lower end portion fitted together in 75
overlying positions at their inner ends, a lon-
gitudinal slot in each of the overlying parts,
a bolt fixed in each one of the parts to extend
through and traverse the slot in the other part,
a series of notches in the edge of the one por-
tion, a single notch in the edge of the other 80
portion and a spring-latch fixed to the edge of
the upper slideable portion of the hame ar-
ranged and combined in the manner set forth
for the purposes stated. 85

2. An extensible hame for horse-collars
comprising a lower portion and an upper por-
tion fitted together to overlie each other at
their inner ends, each of the overlying parts
provided with a longitudinal slot and a bolt 90
fixed in each of the overlying parts to trav-
erse the slot in the other part, a series of notches
in the edge of one of the overlying parts and
a single notch in the other part, a spring-latch
fixed to the edge of the part that has a single 95
notch and a cover fixed to each of the two slide-
ably-connected parts to conceal their inner
ends, arranged and combined to operate in the
manner set forth for the purposes stated.

JAMES H. WINTEROWD.
